Patented May 26, 1959

185,332

FLEXIBLE BOTTLE

Robert P. Vuillemenot, Oradell, N.J., assignor to The Procter & Gamble Company, Cincinnati, Ohio, a corporation of Ohio

Application September 5, 1958, Serial No. 52,515

Term of patent 14 years

(Cl. D58—6)

The rear and side not shown are the same as the front and side, respectively, shown.

I claim:

The ornamental design for a flexible bottle, as shown and described.
